UNITED STATES PATENT OFFICE.

JOHANN SCHMITT, OF COBLENZ, PRUSSIA, GERMANY, ASSIGNOR OF TWO-
THIRDS TO JEAN B. COBLENZER, OF SAME PLACE, AND CARL GUSTAV
ROMMENHÖLLER, OF ROTTERDAM, NETHERLANDS.

KNITTING-MACHINE.

SPECIFICATION forming part of Letters Patent No. 391,084, dated October 16, 1886.

Application filed July 6, 1887. Serial No. 243,492. (No model.)

To all whom it may concern:

Be it known that I, JOHANN SCHMITT, a subject of the King of Prussia, German Emperor, residing at Coblenz, in the German Empire, 5 have invented certain new and useful Improvements in Knitting-Machines, of which the following is a specification.

My present invention involves improvements on my machine for knitting stockings, 10 &c., for which I filed application for Letters Patent in the United States May 12, 1887, Serial No. 238,021, the essential features of which are a rotating spiral and an oscillating needle which catches the meshes from one end of the 15 spiral, the said needle being displaceable and movable in such a manner that the paths or courses described or traveled over by it may be made to incline from opposite directions to a plane laid through the axis of the bent 20 spiral.

My improvements, described hereinafter, relate to a mesh-turner operating in connection with such a spiral and coacting needle, by means of which it is possible to form ribbed 25 knitting correctly.

Before describing the construction of the mesh-turner and the way in which it acts it is necessary to describe the principle of this kind of knitting.

When a woman wants to knit ribbed work in knitting stockings, she puts the needle alternately from the inside and from the outside into the last mesh that is on the knitting-needle. With this needle she draws a new mesh 30 from the outside through one old mesh, and then draws a second new mesh from the inside through another old mesh, and thus forms two new meshes which lie opposite each other. These meshes are termed "right" and "left" 35 meshes. This distinction is not very clear, for a mesh which, when seen from the outside of the knitted fabric, is left, when seen from the inside is right. Owing to this the terms "right" and "left" meshes will not be used in this 40 specification; but instead of them it will be said that meshes have been drawn in either from the outside or the inside. As the knitting is a hose, there can be no mistaking of these expressions. If the knitting is done in 45 the way described in my application filed May 50

12, 1887, Serial No. 238,021, the needle *n*, hereinafter referred to, must always form meshes which have been drawn in from the outside. I term them, briefly, "outside meshes." The needle *n* passes from the outside through the 55 falling-off mesh. In order to be able to form with this needle *n*, which is always moved and oscillated regularly, meshes that lie opposite to those just described, or, in other words, to form inside meshes, the following conditions 60 are necessary: First of all a mesh-turner must be applied between the needle *n* and spiral end *s*. This mesh-turner must turn the mesh that falls off end *s* by one hundred and eighty degrees before the needle *n* passes through the 65 old mesh. The needle *n* passes, therefore, from the inside through this mesh of the hose, and consequently an inside mesh is formed.

The mesh-turner can be arranged in two ways, either with a stationary or with a movable oscillation-axle. Both modifications are represented in the drawings.

For the sake of greater clearness, the mesh-turner with a movable oscillation-axle will be described first.

In the drawings, Figure 1 shows in front view the knitting-machine with the mesh-turner lying before it. Fig. 2 shows a top view thereof in a partial section through line *xy* of Fig. 1. Fig. 3 shows a side view of the 80 machine. Fig. 4 shows a front view of the spiral ends and the mesh-turner. Fig. 5 shows a top view of the same. Figs. 6 to 13 show different positions of the spiral ends and of the mesh-turner during the formation of a twisted 85 mesh, the mechanisms for moving the mesh-turner being not shown in these figures. Fig. 14 shows a front view of the spiral ends and the position of the mesh-turner during the formation of a common mesh. Figs. 15 to 17 90 show a modification of the mesh-turner in different positions. Fig. 17^a shows detailed views of the modified mesh-turner.

The machine in general is similar to that shown and described in my application filed 95 May 12, 1887, Serial No. 238,021, and the different main parts will therefore herein be briefly referred to.

s is the knitting spiral with its two ends, *s's*.

n is the needle through which the yarn runs. 100

$w^0 v^0$ are the driving-axes for rotating the knitting-spiral. In front of the oscillating needle n moves the bent mesh-turner m .

The motion and application of the mesh-turner are as follows: The sickle shaped bent mesh-turner $m m'$, Fig. 4, is firmly connected with a cog-wheel, 1, which revolves on the axle 2 of the arm 3. The arm 3 is in its turn firmly connected with the cog-wheel 4, which sits loose on the axle 5. The bearing of the axle is in the support T' , and the axle cannot rotate in it. The axle bears the non-rotating sector 6, which gears into the cog-wheel 1. The rack T^2 is moved to and fro by lever T^3 and curve-disk T^4 , and whenever it moves the cog-wheel 4 oscillates, the mesh-turner $m m'$ being forced to oscillate also, which it does in the way shown in Figs. 6 to 13. The center of the mesh-turner describes a semicircle, and the sickle of the mesh-turner likewise turns by one hundred and eighty degrees. This turning of the sickle serves to turn the mesh, or, in other words, to form an inside mesh. It proceeds in the following way: 15 Whenever the slide-roller T^5 of the lever T^3 is in a hollow of the curve-disk T^4 , Fig. 2, the mesh-turner is in the position shown in Fig. 6. The spring T^6 makes roller T^5 lie constantly against disk T^4 . In Fig. 6 the needle n has just hung up the mesh $x^0 x'$ on end s^0 of the spirals, and the spiral end s' , which turns in the direction of the arrow, will drop the mesh x in a moment. This would occur if the sickle m of the mesh-turner $m m'$ did not pass into the mesh from the right and catch it up.

Fig. 7 shows the position of the mesh-turner m when it has turned so far and when its center has sunk so much that it holds the mesh securely. It must be observed that the side 40 of the mesh turned toward the sickle-arm m' was that which was on the outside of the hose. The side that is turned toward the sickle-point has therefore been the inside of the mesh. During this time the needle n recedes completely. Fig. 8 shows it in its extreme position. In Fig. 9 the needle n has advanced again, and in Fig. 10 the sickle of the mesh-turner is in such a position that when the needle n advances it can pass into the inside of the mesh 45 x . In doing so the needle passes close behind the mesh-turner. The mesh-turner has thus completed its one oscillation. It recedes then, and the contrary oscillation takes place. Now it draws itself out of the turned mesh, as it is shown in Figs. 11 and 12. The mesh x , which has been taken off the spiral end s' and is now hanging on the needle n , in combination with the mesh $x^3 x^4 x^5$, which is hung up on s^2 when the needle has advanced enough, Fig. 13, 50 forms an inside mesh, for $x^3 x^4 x^5$ has been conducted into the old mesh x from the inside.

In Figs. 6 to 13 the driving-wheels for the mesh-turner are not shown, but the course of the axle of the mesh-turner is indicated by a 65 dotted line. When the needle recedes, Figs. 6 and 7, the hanging mesh slips off the needle n .

Fig. 7 shows the mesh B when it has slipped off and is hanging in mesh $x' x^2$.

The motion of the mesh-turner is dependent, as is evident, on the curve of the curve-disk. 7c If the elevation is so slight that the mesh-turner is moved a little only out of the position represented in Fig. 6, the mesh-turner will only catch up the falling mesh and hold it, as shown in Fig. 14. The mesh-turner may be caused 75 to remain so long in this position that the needle n will reach the position in Fig. 10, and the needle will pass then from outside into the unturned mesh. A common outside mesh will be thus formed, and the mesh-turner, which 80 has performed only a short forward oscillation, will move back then and draw itself out of the mesh. The latter is then hanging on the needle n , which on moving forward hangs up a 85 loop as a new common outside mesh on s^2 , according to the device in the curve-disk, to make alternately outside and inside meshes or to make two outside meshes successively and two inside meshes. This alternate formation 90 of meshes is automatic and occurs on each revolution of the axle.

In the place of this doubly oscillating mesh-turner, a mesh-turner with a stationary oscillation-axe may be employed, as is shown in Figs. 15 to 17a. In this case the oscillation-axe 95 o' of the mesh-turner m is placed between the two spiral ends $s' s^2$. An oscillating motion is given to this axe o' by the curve-disk T^4 , roll T^5 , lever T^3 , and rack-bar T^2 in the same way as it is shown in the case of axle 5 in Figs. 1 to 100 3. I will describe first the shape of this mesh-turner more exactly. It has three ribs, $r^1 r^2 r^3$, Fig. 5a, the two last-named ribs being set 105 opposite each other and the mesh-turner being slightly narrow at that part on which the said ribs $r^2 r^3$ are. In addition to this the mesh-turner has a slit, i^2 .

The working (action) of this oscillating mesh-turner is as follows: The mesh x , that falls off end s' , is caught up by the mesh-turner, 110 which, owing to its oscillating motion in the direction of the arrow v , Fig. 15, enters the mesh from the inside and holds it up. If a common outside mesh has to be formed, the mesh-turner remains in the position shown in 115 Fig. 15, and on its course the needle n will enter the mesh x from the outside. The ribs $r^2 r^3$ assist the needle in entering the mesh, for they form a hollow under the mesh x while it lies on them, and into this hollow the needle 120 can enter with ease. In taking up the mesh the needle passes between the two ribs, catches up the mesh, and hangs it up on spiral end s^2 . The mesh-turner may remain in its position till the needle has retired again and has drawn 125 itself out of the mesh-turner; but the mesh-turner can also go back before that; but, if an inside mesh has to be formed, the mesh-turner does not remain in the position indicated in Fig. 15, but continues to rotate in the 130 direction of the arrow v . In continuing this oscillating motion in the direction of arrow v

the mesh-turner will slide still farther into the mesh x , and finally carries the mesh along with it, as shown in Fig. 16. It must be noticed that during the oscillation of the mesh-turner 5 that has just occurred, and amounted to about one hundred and eighty degrees, the mesh itself has turned very little, for the thick line indicating the outside d of the mesh is still quite on the outside of the machine, and, be- 10 sides that, below. The mesh x will not turn before the mesh-turner has oscillated farther, as is shown in Fig. 17, and in doing that it slides over the rib r' . The mesh is always en- 15 deavoring to move downward, and as it is lifted by the last portion of the forward movement of the mesh-turner, (see Figs. 16 and 17,) and as it resists as much as possible the twist given it by the mesh-turner, it is forced out of the position shown in Fig. 16 into that of Fig. 17. 20 In Fig. 16 the mesh lies over the narrowest part of the mesh-turner; but owing to the con- tinued movement it slips onto the broader part, as shown in Fig. 17. When the mesh is 25 in this position, the needle n crosses the mesh- turner. As is evident from Fig. 17, the needle enters the mesh from the former inside of the mesh x , and in this way a twisted or in- 30 side mesh is formed. After the new mesh has been hung up, the mesh-turner withdraws

A characteristic peculiarity in the arrangement of the mesh-turner is, that it oscillates round an axle lying in front of the two ends of the bent spiral. This oscillation-axle of 35 the mesh-turner may either be stationary or may perform a motion of its own. Another characteristic peculiarity of this mesh-turner is that it forms the ribs in the knitting by merely hanging up and holding fast a certain 40 number of the meshes of the hose without turn- ing them, and by turning a certain number of the meshes by about one hundred and eighty degrees, by which action a ribbed appearance is given to the hose. 45

This mesh-turner turns the mesh that falls off the spiral by one hundred and eighty degrees before the knitting-needle passes through this mesh, and forms a new mesh. The purpose of this mesh turner is to enable the pro- 50 duction of ribbed knit fabric such as is com- monly seen in the upper ends and legs of stockings. With the aid of this mesh-turner this ribbed knitting is performed by one nee- 55 dle without its being necessary to unthread and rethread it. The mesh-turner oscillates by about one hundred and eighty degrees. In this case the mesh is turned round completely, and owing to that it is of great surety for the needle passing through the turned mesh.

For the purpose of forming the inside mesh 60 the spiral end s' must be displaced from its usual position and must be turned back by about ninety degrees, so that the position of the needle n to the spiral end s' is altered. This gives the mesh-turner time enough to 65 seize the mesh falling off the spiral end s' and to turn it before the needle passes through the mesh. When the spiral end s' is in the old position it has hitherto occupied, (application Serial No. 238,021,) the mesh falls off it directly 70 onto the needle n , that stands under it.

This mesh-turner assists the formation of not only inside but also of outside meshes, be- 75 cause the spiral end s' is turned back by ninety degrees. If it did not work, the outside meshes would fall off the spiral end s' without there being anything to take them up. The needle n is not yet arrived with its point under the spiral end s' , which has been turned back. The mesh-turner must therefore also catch up 80 the outside meshes when they fall off and hold them till the needle n passes through them from the outside. As the mesh-turner does not turn the mesh in this case, the motion of the mesh-turner must be very slight, of course. 85 It must move forward only far enough to catch up the mesh and hold it. It has not to turn the mesh in this case, for to form an outside mesh the mesh lies just right for the needle. 90

Having now particularly described and as- 95 ccertained the nature of my invention and in what manner the same is to be performed, I declare that what I claim, and desire to se- cure by Letters Patent of the United States, is—

1. In knitting-machines, the combination of an oscillating mesh-turner, m , and the bent spiral s with an eyed needle, n , for the purpose as described. 95
2. In knitting-machines, the combination of an oscillating mesh-turner, m , the bent spiral s , and an eyed needle, n , with the oscillating arm 3, the cog-wheels 1 and 6, and shaft 5, for the purpose as described. 100
3. The combination of a bent spiral, s , with an eyed needle, n , and an oscillating mesh- turner, m , oscillating arm 3, the cog-wheels 1 and 6, cog-wheels 4, rack T^2 , lever T^3 , axle 5, and the cam-disk, for the purpose as described. 105

It witness whereof I have hereunto set my 110 hand in presence of two witnesses.

JOHANN SCHMITT.

Witnesses:
